UNITED STATES PATENT OFFICE.

ROBERT NEWTON, OF PROVIDENCE, RHODE ISLAND.

FUEL-ECONOMIZER.

SPECIFICATION forming part of Letters Patent No. 428,405, dated May 20, 1890.

Application filed December 3, 1889. Serial No. 332,391. (No model.)

To all whom it may concern:

Be it known that I, ROBERT NEWTON, of the city of Providence, in the county of Providence and State of Rhode Island, have invented a new and useful Improvement in Fuel-Economizers; and I hereby declare that the following is a full, clear, and exact description of the same, reference being had to the accompanying drawings, forming part of this specification.

This invention has reference to an improvement in the construction of furnaces for steam-generators, adapted to burn bituminous coal, so as to utilize all or nearly all of the volatile gases, prevent smoke, and economize the fuel.

The invention consists in the peculiar and novel construction of the furnace, as will be more fully set forth hereinafter, and pointed out in the claims.

Figure 1 is a longitudinal sectional view showing my improved fuel-economizer furnace in connection with a steam-generator. Fig. 2 is a plan view of the economizer. Fig. 3 is a sectional view on the line X Y in Fig. 1, looking toward the rear.

Similar numbers of reference indicate corresponding parts throughout.

In the drawings, the number 6 indicates the steam-space of the steam-boiler, and the number 7 the water-space; 8, a hot-water chamber connected with the steam-boiler near the water-line, but preferably below the same, by the pipes 9. The chamber 8 extends across the fire-box and is supported at each end in the walls forming the sides of the fire-box. The bearing 10 for the grates forms part of the chamber 8 or may be secured to the same. The hinged dead-plate 11 is also supported by the chamber 8. The tubes 12 are secured at one end to the chamber 8 by means of faced flanges. They are placed on the inclined angle of thirty degrees, or thereabout. The lower ends of the tubes are bent and the ends connected with the bridge-chamber 13 by means of faced flanges, the lower part of the tubes 12 extending vertically for some distance above the bridge-chamber. The bridge-chamber 13 extends across the fire-box and is supported at each end by the walls of the fire-box. The

supporting-bar 14 and the supporting-bar 15 are cast in one piece with the bridge-chamber

or are connected with and supported by the same. The bar 15 is supported on the posts 16, which are placed in front of one of the tubes 12. The spaces between the tubes at 55 their lower vertical length form large open air-spaces. The grates 17 fill up the space between the bridge-chamber and the bridge-wall 19.

The number 18 indicates grate-bars placed 60 between the tubes 12 resting on the bar 15 and the bearing 10. These bars 18 are provided with distance-blocks 20 on each side nearly touching the tubes 12. The bars 18 are each provided with a notch, into which the arm 21 65 projecting from the shaft 22 enters. The rocker-arm 23 projects from the shaft 22. When the rocker-arm 23 is moved up and down, reciprocating motion is imparted to the bars 18 and the upper ends of the bars are 70 raised and lowered. By this motion the coal is moved forward, and this motion is facilitated by the saw-tooth form of the upper edges of the bars.

The bridge-chamber 13 is connected with 75 the water of the steam-boiler by means of the pipe 24, connected with the rear of the steam-generator and the bridge-chamber 13. In furnaces for steam-generators of the usual diameter the bearing-bars supporting the grates 80 are liable to become heated and sag, particularly in the class of furnaces where one grate is placed at an incline above the other.

By the peculiar construction of my improved grate the chambers 8 and 13 are kept 85 cool by the water passing through the same, and as the supports for the grates are formed in one part with these chambers or connected with the same, furnaces of any desired width may be safely constructed.

90 The operation of my improved fuel-economizer is as follows: The coal is placed, either by hand or by a mechanical stoker, on the dead-plate and upper end of the grates 18 and tubes 12, where the same is heated and gradually passes down the inclined grate. During this passage the more volatile portions of carbon are separated by the coking or roasting of the coal, and the solid carbon or coke is delivered to the grate 17. The openings between 95 the tubes 12 permit the entrance of the slice-bar, so that the grate 17 can be kept clean

and a large supply of air can enter through the grate into the fuel, securing a bright fire and a very high temperature. The gases and smoke from the roasting coal on the upper 5 grate pass over the bright fire and flame of the lower grate directed by the bridge-wall toward the boiler. As the spaces between the vertical lower ends of the tubes 12, between the bridge-chambers 13 and the grates 18, are 10 unobstructed, the air from the ash-pit 25 enters and rises between the gases and the bright hot fire of the grate 17 and supplies the requisite oxygen for the complete combustion of the gases and smoke as the same pass over 15 and mix with the hot flame of the lower grate before the products of combustion pass over the bridge-wall to the rear chamber under the boiler. The bridge-chamber 13 is supplied 20 with water by the pipe 24, and this water passing through the tubes 12 absorbs and utilizes the heat of the fire and passes through the chamber 8 and pipes 9 to the steam-generator, thus economizing the fuel and increasing the efficiency of the steam-generator, while the 25 structure is protected against injury from the excessive heat to which it is subjected. As the tubes 12 are bent near their lower end, any variation in their expansion will not affect the joints. Suitable blow-off valves and 30 connections may be made with the bridge-chamber 13, preferably on the end opposite

the end to which the supply-pipe 24 is connected.

Having thus described my invention, I claim as new and desire to secure by Letters Pat- 35 ent—

1. The combination, with the steam-generator, the horizontal grate 17, and the inclined grate 18, of the bridge-chamber 13, connected with the rear water-space of the generator and 40 having the bearing 14 formed integral therewith, the tubes 12, extending vertically in front of the supports 15 and 16 for the grate-bars 12, bent to form an incline, and the chamber 8, provided with the bearer 10, connected with 45 the front of the generator, constructed to form the support for the grate and protect the same, as described.

2. The combination, with the chamber 8, the bridge-chamber 13, and the tubes 12, bent 50 to correspond with the incline of the upper grate and extend vertically in front of the lower grate, of the grate-bars 18, the shaft 22, arms 21, rocker-arm 23, and the hinged dead-plate 11, constructed to yield to the move- 55 ment of the grate-bars, as described.

In witness whereof I have hereunto set my hand.

ROBERT NEWTON.
